UNITED STATES PATENT OFFICE.

THOMAS J. FLAGG, OF NEW YORK, N. Y.

DESIGN FOR A MADE-UP SCARF.

SPECIFICATION forming part of Design No. 19,160, dated June 18, 1889.

Application filed May 24, 1889. Serial No. 312,004. Term of patent 3½ years.

To all whom it may concern:

Be it known that I, THOMAS J. FLAGG, of the city, county, and State of New York, have invented and produced a new and original Design for Made-Up Scarfs, of which the following is a description, reference being had to the accompanying drawing, and to the letters of reference marked thereon, making a part of this specification.

10 Said drawing represents the front of a made-up scarf embodying my design.

The design involves the presentation to the eye at the head of the scarf of a recess A, having the outline of a scalene triangle B C 15 D, whose longer side B C coincides with the neck-line of the scarf. This triangular re-

cessed figure B C D, of unequal sides, is produced, as is illustrated in the drawing, upon that part of the scarf included between the upper edges of its intersecting aprons E F 20 and its neck-line B C.

I claim as new and of my invention—

The design for a made-up scarf, as shown in the accompanying drawing and described in the specification.

In testimony whereof I have signed my name to this specification in the presence of two subscribing witnesses.

THOMAS J. FLAGG.

Witnesses:

A. N. JASBERA,
E. M. WATSON.
